UNITED STATES PATENT OFFICE.

EDWIN E. SLICK, OF PITTSBURG, PENNSYLVANIA.

METHOD OF REROLLING RAILS.

No. 852,983.

Specification of Letters Patent.

Patented May 7, 1907.

Application filed January 19, 1904. Serial No. 189,715.

To all whom it may concern:

Be it known that I, EDWIN E. SLICK, of Pittsburgh, Allegheny county, Pennsylvania, have invented a new and useful Method of 5 Rerolling Rails, of which the following is a full, clear, and exact description, reference being had to the accompanying drawings, forming part of this specification, in which:—

Figure 1 is a side elevation of the roughing 10 stand of rolls; Fig. 2 is a side elevation of the finishing stand of rolls, having the reducing passes arranged to carry out my improved method of re-rolling; and Fig. 3 is a side elevation showing a modified arrangement of 15 the roughing stand of rolls.

The object of my invention is to provide a method for re-rolling worn-out or defective rails of heavy section into rails of lighter section, in a more rapid and economical manner 20 than heretofore possible, and to overcome the difficulties found in existing methods, by preventing over-filling the passes and consequent fins; also in preventing buckling, lapping, and forming of seams which when once 25 formed will carry through the remaining passes and show on the rail when completed, as the steel will not weld at the temperature used in rolling.

One method of re-rolling rails heretofore 30 known has been first to reduce the height of the rail in roll passes with the rail in such position that a line through the center of the head, web and flange was at right angles to the axes of the rolls and then further to reduce 35 the rail through passes with the center line of the head, web and flange of the rail parallel with the axis of the rolls. In this method the work was done by the top and bottom sides of the passes, the vertical sides 40 of the passes merely supporting the material while in the rolls. Another method has been to roll the metal with a line through the center of the head, web and flange of the rails at a slight angle with a line parallel to the axes 45 of the rolls, but with the flange of the rail always normal to the head and web, (i. e., the outer face of the flange at a right angle to a line through the center of the head and web portions of the rail.) The disadvantages of 50 these methods lie in the large number of reducing passes necessary to re-roll a rail, on account of the small amount of reduction possible in order to avoid buckling or lapping in the web of the rail, the forming of seams, 55 and the great difficulty in filling some por-

tions of the passes and in preventing over-filling and consequent fins.

One broad novel feature of my invention lies in bending the section so that the base flange in the live groove of the pass is at an angle of less than 90 degrees to the web while the flange in the dead groove is at an angle greater than 90 degrees.

In Fig. 1, I show five passes I, II, III, IV and V, these being formed between the rolls 65 2, 3 and 4 of a three-high mill. In the first pass as shown, the rail lies horizontally or with its axis parallel to the axes of the rolls. In this pass the flanges and the head are reduced in width, that is, in the direction transversely to the plane of the web. In the next 70 pass II, the section is bent so that the flange 5 in the live groove extends at less than an angle of 90 degrees to the plane of the rail web, while the flange 6 in the dead groove, 75 is at an obtuse angle to such line. In the third pass the section is bent in the other direction so that the flange 5^a in the dead pass is at an obtuse angle, while the flange 6^a in the live groove is at an angle greater than a 80 right angle. In the succeeding grooves down to the final pass, the bending of the shape takes place in each pass, each flange being at an obtuse angle in one pass and at an acute angle, in the next.

In Fig. 2, I show two passes VI, VI, which 85 follow the preceding passes, II, III, IV and V, and through either one of which the rail is passed in coming from the fifth pass. In this figure VII, VII are the finishing passes, 90 in which the base flanges are restored to their normal position, the axial line of the rail is parallel to the axes of the rolls, and the reduction preferably takes place throughout the rail section.

It will be noted that the preliminary pass, 95 wherein the axis of the rail is parallel to the axes of the rolls may be in any one of the first passes; that is in the first pass the rail axis may be at an angle to the axis of the roll, and No. 2 pass arranged with the axis of the rail parallel to the axis of the roll. It will also 100 be noted that the flanges may be restored to their normal position and the rail rolled with its axis parallel to the axes of the rolls, at a 105 pass before the final pass, without departing from my invention.

In Fig. 3 I show another form of the preliminary or roughing stand of rolls. In this 110 form the passes II, III, IV, and V are sub-

stantially the same as those of Fig. 1, while the pass I is an angular pass similar to the second pass. With this set of roughing passes, the finishing passes may be the same as in Fig. 2. It will be noted that in both forms of roughing passes, the shape is bent so that the flanges are out of their normal position, in the angular passes.

By inclining the one part of the flange at a greater than the normal and the other part at less than the normal angle of the flange with the head and web portions of the rail being rolled, I am enabled to reduce the metal both horizontally and vertically at the same time and to greatly increase the amount of reduction in each pass. By means of the finishing passes VI and VII shown in Fig. 2, the rail is further reduced and formed to the finished shape, the flange being restored to normal position relatively to the web. In this way the time required to re-roll is greatly reduced and the output of the mill largely increased; the possibility of buckling andlapping in the web portion of the rails is removed, and the forming of fins and seams during the rolling. One groove of the pass for the flange may be inclined to a greater or less angle than the normal angle of the flange with the head and web portions of the rail, the groove for the other flange remaining normal. The web may be bent intermediately so that the flanges are out of their normal position to a part only of the web, and other variations in the roll passes may be made without departing from my invention.

I claim:

1. The method of re-rolling rails, consisting in feeding a rail through a rolling pass, bending one of the base flanges inwardly therein to an acute angle with the web, simultaneously reducing the shape, and finally restoring the flange to its normal position and finishing the section in a later pass or passes; substantially as described.

2. The method of re-rolling rails, consisting in feeding the rail through a rolling pass with its web in an inclined position relative to the axes of the rolls, simultaneously bending one of the base flanges inwardly to an acute angle to the web, and reducing the shape in both directions, and finally restoring the flange to its normal position and finishing the section; substantially as described.

3. The method of re-rolling rails, consisting in feeding the rail through a rolling pass with its web at an angle to the axes of the rolls, bending the base flange in the live groove inwardly to an acute angle with the web, simultaneously reducing the shape in both directions, and finally restoring the flange to its normal position and finishing the section; substantially as described.

4. The method of re-rolling rails, consisting in feeding the rail into a rolling pass, bending the flange in the live groove to an

acute angle with the web, and reducing the section, then feeding the section into another pass with the other flange in the live groove, and bending said other flange inwardly, and finally restoring the flanges to normal position and finishing the section in a later pass or passes; substantially as described.

5. The method of re-rolling rails, consisting in feeding the rail through a rolling pass, bending the section therein so that the angle between the web and the flange in the live groove is less than a right angle, simultaneously reducing the shape, and finally restoring the flange to its normal position and finishing the section in a later pass or passes; substantially as described.

6. The method of re-rolling rails, consisting in feeding the same through rolling passes, bending the shape so that the angle between the web and the flange in the live groove is less than a right angle, then feeding the shape through another pass with the other flange in the live groove, and simultaneously bending the shape so that the angle between the web and the other flange is less than a right angle, and finally restoring the flanges to their normal position and finishing the section; substantially as described.

7. The method of re-rolling rails, consisting in feeding the section through rolling passes with the web at an angle to the axes of the rolls, and alternately bending the opposite base flanges to an angle with the web which is less than a right angle in the successive passes; substantially as described.

8. The method of re-rolling rails, consisting in feeding the section through a succession of rolling passes with the plane of the web at an angle to the axes of the rolls, alternately feeding the opposite base flanges in the live groove, and alternately bending said flanges so that the angle between the flange in the live groove and the plane of the web is less than a right angle, and at the same time bending the shape so that the flange in the dead groove is at an obtuse angle to the web; substantially as described.

9. The method of re-rolling rails consisting in reducing the rail in a pass with its axis at an angle to the roll axes and bending the section so that the flange in the live groove is at acute angle to the web and the flange in the dead groove at an obtuse angle thereto; substantially as described.

10. The method of re-rolling rails consisting in bending the shape so that one flange is at an angle of less than 90 degrees to the web, and the other flange is at an angle of more than 90 degrees to the web, passing the first named flange through the live groove, and the latter obtuse angle flange through the dead groove, then bending in the opposite direction, and passing the metal with the opposite flanges in the respective grooves, and then restoring the flanges to their normal po-

sition and finishing the section in a later pass or passes; substantially as described.

11. The method of re-rolling rails, consisting in first rolling the rail with its axis parallel to the roll axes, then bending the shape so that the angle between the web and the flange in the live groove is less than a right angle, simultaneously reducing the shape, and finally restoring the flange to its normal position and finishing the section in a later pass or passes; substantially as described.

12. The method of re-rolling rails, consisting in rolling the rail with its axis parallel to the roll axes, then rolling the rail with its axis at an angle to the roll axes, and simultaneously bending it so that the angle between the web and the flange in the live groove is less than a right angle, and finally restoring the flange to its normal position and finishing the section; substantially as described.

13. The method of rolling flange shapes, consisting in feeding the shape through a rolling pass, bending the section therein so

that the angle between the web and the flange in the live groove is less than a right angle, simultaneously reducing the shape, and finally restoring the flange to its normal position and finishing the section in a later pass or passes; substantially as described.

14. The method of rolling flanged shapes, consisting in feeding the shape through a rolling pass with its web at an angle to the axes of the rolls, bending the section therein so that the angle between the web and the flange in the live groove is less than a right angle, simultaneously reducing the shape, and finally restoring the flange to its normal position and finishing the section; substantially as described.

In testimony whereof, I have hereunto set my hand.

EDWIN E. SLICK.
